2,482,942

TEXTILE ASSISTANTS MADE FROM SYNTHETIC TANNING AGENTS AND AMMONIUM COMPOUNDS

Eduard Schwager and Jakob Bindler, Basel, Switzerland, assignors to J. R. Geigy A-G., Basel, Switzerland, a firm of Switzerland

No Drawing. Application June 22, 1945, Serial No. 601,056. In Switzerland July 4, 1944

9 Claims. (Cl. 260—45.1)

1 It has been found that new technically valuable reaction products are obtained by causing organic compounds containing sulfonic groups and possessing tanning properties to react with quaternary ammonium compounds containing higher molecular aliphatic or cycloaliphatic radicals. The new products may be used particularly as textile assistants. They possess the surprising properties of being able to slacken down the drawing of dyestuffs and thus to guarantee a levelling effect; simultaneously the new products are especially suitable for the stripping of vat dyestuffs. Besides, they can also be used as dressing and finishing agents.

It is known already to combine quaternary ammonium compounds, which contain higher-molecular radicals, with compounds containing sulfonic acid groups. Thus it is known for instance to use vat dye-baths, which contain surface-active compounds capable of dissociation, which compounds are cation-active, such as for instance lauryl pyridinium sulfate, and to add surface-active compounds which are capable of dissociation and are anion-active during the dyeing operation, such as fat alcohol sulfonates. The cation-active compound produces a very extremely retarding effect on the vat-dyestuff, which corresponds almost to a reserving effect, whereas the anion-active compounds annul more or less largely the effect of the former compound. According to this method it is possible by means of addition of the second assistant to reach any desirable degree of the dyestuff being initially reserved, so that it is possible to cause even the complete drawing of the dye-bath. Thus the effect or properties of both the auxiliary products neutralize each other.

For the same purpose also similar combinations have been proposed. Thus for instance it is known to prepare vat-dye-baths containing alkali-stable ammonium compounds reacting as a base and being soluble or dispersible in water, the said ammonium compounds possessing at least one radical of six or more carbon atoms, and to add protecting colloids or dispersing agents which can also contain sulfonic acid groups; among the latter compounds may be enumerated for example: castor oil sulfonic acid, sulfonation products of the oleic acid ethyl anilide, etc.

Furthermore, it is known to strip vat dyeings by 50 or by patent literature, such as naphthalene-sul-

2 treating the same with alkaline baths containing, besides a reducing agent, a quaternary ammonium salt with high-molecular hydrocarbon radicals and also a purifying agent of the type of the high-molecular aliphatic sulfonic acids or of sulfuric acid esters of fatty alcohols. When working according to this method vat dyestuffs, which otherwise can be stripped only with difficulty, may be stripped easily also in the presence of azo dyestuffs.

15 Moreover, it is known to increase the effect of wetting agents containing sulfonic acid groups, like dibutylated naphthalene sulfonic acid, by a combination with organic ammonium bases, particularly with those containing an aliphatic radical of 5 to 11 carbon atoms.

20 However, from these and other publications it could not be derived that new, technically valuable products are obtained by combining higher molecular quaternary ammonium compounds with organic compounds containing sulfonic groups, and possessing tanning properties. When compared with similar known combinations the new products show the advantage of a superior 25 efficacy, for instance when used as assistants for dyeing with vat dyestuffs, with acid or direct dyestuffs, etc. In the new combinations the quaternary compounds have surprisingly lost their properties to mostly precipitate the dyestuff, this feature being of importance especially for their use 30 in vat-dyeing and wool-dyeing.

35 As quaternary ammonium compounds with higher molecular, aliphatic or cycloaliphatic radicals the known ones may be used and particularly the following ones may be enumerated for example: phenyl-octadecyl-dimethyl ammonium-methyl-sulfate, trimethyl-cetyl-ammonium-bromide, di-isopropylbenzyl-trimethyl-ammonium-bromide, dodecyl-pyridinium-sulfate, dodecyl-hydroxymethyl-pyridinium-chloride, dodecyl-benzene - α - trimethyl-ammonium-methyl - sulfate, methyl-sulfate of trimethylaminoacet-N-dodecyl-anilide, 4-stearylaminophenyl-trimethyl-ammonium-methyl - sulfate, stearylaminooethyl-trimethyl-ammonium-methyl-sulfate and the like.

40 As compounds containing sulfonic acid groups and having tanning properties, there may be used any condensation products known in the trade 45 or by patent literature, such as naphthalene-sul-

fonic acid formaldehyde condensation products, phenol- or naphthol sulfonic acid formaldehyde condensation products, condensation products from unsulfonated partly or completely sulfonated dihydroxydiarylsulfones, aromatic sulfonic acids and formaldehyde, phenolsulfonic acids, urea and formaldehyde or condensation products of unknown constitution.

According to the chemical constitution of the compounds the final products are partly soluble in water without special measures and partly only when an excess of the tanning compound is present. The new products are also soluble in alkalis. Quaternary compounds which are stable or unstable to alkalis yield the same good results. In accordance with the ratios applied the properties of the final products will change, this being often very valuable for the production of special effects. The new products can be made as such and isolated for instance by salting out, by evaporation, etc., but, on the other hand, they can be produced previously with success in the application baths.

The following examples will illustrate the present invention, without limiting the same; the parts are by weight, unless otherwise stated.

EXAMPLE 1

20 parts of phenyl-stearyl-dimethyl-ammonium-methyl-sulfate are completely dissolved by stirring in 1600 parts of water, the temperature being raised at the end of the operation to about 45-50° C. Then a solution of 240 parts by volume of a liquid tanning substance in 2000 parts of water is caused to flow thereinto in a thin jet, the said tanning substance being obtainable by condensation of crude cresol sulfonic acid, urea and formaldehyde according to French Patent 46,179, being a patent of addition to French Patent 660,008, and its solution being maintained at 45°-50° C. The new reaction product thus is produced after some time, while a strong turbidity occurs. Now, 600 parts of sodium chloride are added, whereby the new compound is completely precipitated. The temperature is increased for a short time to 50° C. and then is cooled down to 20-25° C. The precipitate is filtered by suction and washed with water. After drying at 50°-60° C. in vacuo a yellowish-brown powder is obtained which is clearly soluble in water on addition of a base.

EXAMPLE 2

10 parts of phenyl-stearyl-dimethyl-ammonium-methyl-sulfate are dissolved in 40 parts of water at 50°-60° C.; then 50 parts of a condensation product obtainable from naphthalene sulfonic acid and formaldehyde are introduced under stirring on the water-bath and heated until a homogeneous viscous solution has been formed.

EXAMPLE 3

A solution of 15 parts of methyl-sulfate of trimethyl-aminoacet-N-dodecylamide in 800 parts by volume is allowed to flow in form of a thin jet into a solution of 120 parts by volume of a synthetical tanning substance, prepared according to French Patent 723,883 by condensation of dihydroxy diphenyl sulfone with naphthalene-sulfonic acid and formaldehyde, in 1200 parts by volume of water, the said solution being maintained at 40°-50° C. A milky turbidity is produced. On addition of sodium chloride the new product is precipitated. Then it is cooled, filtered and the filter-mass is dried in vacuo.

Thus there is obtained a yellowish powder being clearly soluble in water, when adding a base.

A similar final product is also obtained by means of any analogous tanning substance containing sulfite lye.

EXAMPLE 4

10 parts of methyl-sulfate of trimethylaminoacet-N-dodecylamide are dissolved in 100 parts by volume of water and combined gradually at 50° C. with an aqueous solution of a synthetical tanning agent obtainable according to French Patent 847,029, i. e. a condensation product from phenol monosulfonic acid and naphthalene monosulfonic acid. While a strong turbidity occurs, the formation of the new product is effected, the latter being precipitated by means of sodium chloride. After the usual working up a yellowish powder is obtained which is soluble in water on addition of an alkali.

According to the indications made in the above examples also the following compounds may be combined together: dodecylhydroxymethyl-pyridinium-chloride+tanning substance obtainable according to French patent of addition 45,250, addition to French Patent 723,883, trimethyl-(α -heptadecylbenzyl)-ammonium - methyl-sulfate+tanning substance according to French patent of addition 46,179, addition to French Patent 660,008, trimethyl-octadecenyl - ammonium - methyl-sulfate+tanning substance according to French patent of addition 46,179, methyl-sulfate of trimethyl - aminoacet-N-octadecylamide+tanning substance according to French Patent 46,179 and so on.

Instead of the compounds mentioned in the above examples, also the other compounds enumerated in the introducing part of the specification may be used, whereby reaction products with similar properties are obtained.

It will be manifest to the skilled in the art from the above examples, and more particularly from Examples 1, 2 and 4, that a minimum of two sulfonic acid groups are present for each mol of quaternary ammonium compound used in the reaction.

EXAMPLE 5

A strand of staple fibre is dyed in a dye-bath ratio of 1:30 in the usual manner with 1% of 50 Tinone-chloroviolet RN (Schultz Farbstofftabellen, 7th edition, vol. 2, page 213) at 60° C. in $\frac{3}{4}$ hour. If 0.4 or 2 grs. respectively of the reaction products obtainable according to Example 1 or 2 respectively are added per litre of dye-bath, 55 a strong retarding power, a better levelling power and a better dyeing is obtained than with a dye-bath containing no assistant. Besides, the leuco dyestuff is dissolved in a much more highly dispersed manner, the vat is almost clear and thus 60 much more stable; the vat contains nearly no "vat flower" and has, therefore, a less tendency to produce precipitates which smear the dyed material and yield uneven dyeings which are not fast to rubbing.

EXAMPLE 6

Stripping power of dyed vat-dyestuffs

Staple fibres dyed with 2% of Tinone-chloro-blue BL (Schultz Farbstofftabellen, 7th edition, 70 vol. 2, page 212) are treated in a bath containing 4 grs. of sodium hydrosulfite and 16 ccm. of caustic soda dye of 36° Bé per litre. The stripping effect is relatively small. The same is substantially increased by adding to the stripping bath per litre thereof 2 grs. of the compound accord-

ing to Example 1 or of that of Example 2.

If, after the completion of the stripping action, a sufficient quantity of a wetting agent, such as di-isobutyl-naphthalene-sulfonic acid, is added to the bath, the leuco-vat-dyestuff stripped can again be used for the dyeing of the fibre from this bath. This method is advantageously applied for correcting or over-dyeing defective portions.

EXAMPLE 7

Retarding power on dyeing with slightly acid dyestuffs

Carpet-yarn is dyed in the dye-bath ratio of 1:30 with 2% of Polar-red B concentrated (Schultz Farbstofftabellen, 7th edition, vol. 2, page 175) under addition of 10% of Glauber's salt and 3% of 30% acetic acid. Then at 60° C. the wool is introduced into the dye-bath supplied with all of the additional products, the mixture being heated to 95° C. and maintained at this temperature for one hour. Then it is rinsed and dried. When per litre of dye-bath 2 grs. of a reaction product disclosed in Example 2 are added, there may be observed a strong retarding power, this being in contrast with ordinary dyeings. In contradistinction to the quaternary compounds used alone the new reaction products do not practically influence the shade of the dyeings.

EXAMPLE 8

Retarding power on dyeing with direct dyestuffs

Staple fibre rags are dyed in the dye-bath ratio of 1:40 with 3% of diphenylcatechine DB (Schultz Farbstofftabellen, 7th edition, vol. 2, page 83) at 95° C. under addition of 30% of Glauber's salt. The retarding power is examined by hanging one staple fibre rag first for 5 minutes in such a manner into the dye-bath that only one half thereof is dipped in, the whole rag being subsequently dyed at 95° C. for 40 minutes. Then it is rinsed and dried. Without addition of a condensation product of the present invention dyeings are produced, the half portion thereof being dyed in an uneven way, that is to say the levelling of the dyeings is unsatisfactory. However, if 2 grs. per litre of a condensation product disclosed in the present specification, for instance of the product obtainable according to Example 2, are added, dyeings of brighter, but distinctly more even shades are obtained.

What we claim is:

1. Process for the manufacture of a water-soluble textile assistant, which comprises reacting in aqueous medium a synthetic tanning agent containing sulfonic acid groups with a cation-active quaternary ammonium compound containing a hydrocarbon radical selected from the group consisting of aliphatic and araliphatic hydrocarbon

radicals containing 12 to 24 carbon atoms, a minimum of two sulfonic acid groups being present for each mol of quaternary ammonium compound, and finally rendering alkaline the obtained product, whereby it is converted into water-soluble form.

2. A process for the manufacture of a water-soluble textile assistant, which comprises reacting in aqueous medium a synthetic tanning agent

10 containing aromatically bound sulfonic acid groups with a cation-active quaternary ammonium compound containing a hydrocarbon radical selected from the group consisting of aliphatic and araliphatic hydrocarbon radicals containing 12 to 24 carbon atoms, a minimum of two sulfonic acid groups being present for each mol of quaternary ammonium compound, and finally rendering alkaline the obtained product, whereby it is converted into water-soluble form.

15 20 As a textile assistant, a water-soluble alkalinized reaction product obtained by the process of claim 2.

25 25 The process according to claim 2, wherein the tanning agent is a condensation product from naphthalene sulfonic acid and formaldehyde, and the quaternary ammonium compound is phenyl-dimethyl-stearyl-ammonium-methosulfate.

30 35 As a textile assistant, the water-soluble alkalinized reaction product obtained by the process of claim 4.

35 40 The process according to claim 2, wherein the tanning agent is a condensation product from cresolsulfonic acid, urea and formaldehyde, and the quaternary ammonium compound is phenyl-dimethyl-stearyl-ammonium-methosulfate.

45 45 As a textile assistant, the water-soluble alkalinized reaction product obtained by the process of claim 6.

50 55 The process according to claim 2, wherein the tanning agent is a condensation product from phenol-monosulfonic acid and naphthalene monosulfonic acid, and the quaternary ammonium compound is the methosulfate of trimethyl-aminoacet-N-dodecylanilide.

45 50 As a textile assistant, the water-soluble alkalinized reaction product obtained by the process of claim 8.
